(57) **CLAIM**

The ornamental design for an electronic device, as shown and described.

DESCRIPTION

FIG. 1 is a front perspective view of an electronic device, showing the new design in an extended position; FIG. 2 is a rear perspective view of FIG. 1; FIG. 3 is a front elevational view of FIG. 1; FIG. 4 is a rear elevational view of FIG. 1; FIG. 5 is a right-side elevational view of FIG. 1; FIG. 6 is a left-side elevational view of FIG. 1; FIG. 7 is a top plan view of FIG. 1; FIG. 8 is a bottom plan view of FIG. 1; FIG. 9 is a perspective view thereof, illustrated in a fully collapsed configuration; FIG. 10 is a perspective view thereof, illustrated in a collapsed configuration with a keyboard extended; FIG. 11 is a front elevational view of FIG. 9; FIG. 12 is a right side elevational view of FIG. 9; FIG. 13 is a left-side elevational view of FIG. 9; FIG. 14 is a top plan view of FIG. 9; and, FIG. 15 is a bottom plan view of FIG. 9.

The broken line showing of the keys in FIGS. 1, 2, 7, and 10, and the hinges in FIG. 14 is for environmental purposes only and forms no part of the claimed design.
